UNITED STATES PATENT OFFICE.

CHARLES W. BREWSTER, OF NEW YORK, N. Y., ASSIGNOR TO THE BREWSTER-GOLDSMITH CORPORATION, INC., OF NEW YORK, N. Y., A CORPORATION OF NEW YORK.

ANTISUBMARINE DEVICE.

1,331,800.

Specification of Letters Patent. Patented Feb. 24, 1920.

Application filed February 16, 1918. Serial No. 217,490.

To all whom it may concern:

Be it known that I, CHARLES W. BREWSTER, a citizen of the United States, and a resident of the borough of Manhattan, in 5 the city, county, and State of New York, have invented certain new and useful Improvements in Antisubmarine Devices, of which the following is a specification.

The object of this invention is to indicate 10 the presence and movements of submarines, so that they may be readily destroyed by patrol vessels. This is accomplished by causing the submarine to attach to itself a marker, which it tows along upon the 15 surface of the water. The apparatus herein-after described comprises a buoy, a magnetic attacher, and means for anchoring the same under water together with means for casting off the anchor when the attacher 20 affixes itself to a submarine, and means for also paying out the upward extending cable, so that the buoy may then ride upon the surface. A suitable number of these devices are placed in localities likely 25 to be visited by submarines, and each buoy may have a number of attachers connected therewith. The attachers are preferably provided with electro-magnets, normally de-energized, and adapted to be supplied with 30 current from a source in the buoy, the closing of the circuit and the casting off of the parts below the particular attacher which may be affected being brought about by suitable means, operated through contact with 35 the submarine. Each attacher is desirably provided with a circular pathway or fender, extending in both directions from its active face, so that, if a submarine brushes against the fender at any side, the attacher will be 40 rolled around until its magnetic pole and actuating trigger are brought against the side of the vessel. These and various other features of the invention will become apparent as the specification proceeds.

45 In the drawings:

Figure 1 is a view showing a complete device in use;

Fig. 2 is a back view of the lower attacher shown in Fig. 1;

50 Fig. 3 is an elevation of the buoy;

Fig. 4 is a vertical section through the same;

Fig. 5 is a plan view of the attacher of Fig. 2;

Fig. 6 is a section through the same taken 55 in a vertical plane;

Fig. 7 is a view similar to Fig. 6 on a larger scale, showing a portion of the upper attacher of Fig. 1;

Fig. 8 is a wiring diagram; and

Fig. 9 is a fragmentary horizontal section on the line 9—9 of Fig. 4.

Fig. 1 shows a buoy 2 and two attachers 3 and 3^a anchored below the water level 4 by a suitable anchor 5. A cable section 6 connects the buoy with the upper attacher 3^a, another section 7 extends from this attacher to the lower attacher 3, and still another cable section 8 passes downward from the attacher 3 to the anchor. It will be understood, of course, that a series, consisting of any number of attachers, may be connected at different heights between the buoy and anchor. Two attachers are sufficient to illustrate the invention, and I shall for convenience refer to the upper and the lower attacher, but it will be understood that precisely the same principles will apply with a greater number.

The buoy comprises a suitable water-tight 80 casing containing an electric battery 9 in its upper portion. In a lower compartment 10 a reel 11 is mounted to turn upon a horizontal axis. This reel holds a large reserve supply of the cable 6, which passes downward 85 through a bottom exit 12. This exit is rendered tight by a flexible impervious ring 13, preferably of rubber and of substantially U-shaped cross-section, the margins of which are clasped upon the exit and upon 90 the cable, respectively, by constricting bands 14. The reel 11 is fixed upon an axle 15, which turns in bearings 16 and 16^a in the buoy, and the said axle may contain an insulating core 17, through which passes an 95 axial electric conductor 18. One end of this conductor is connected by a lead 19 with an electrical conductor 20, which extends throughout the length of the cable section 6, which is wound upon the reel and extends 100 downward to the attacher 3. The cable section 7, it may be here noted, contains a similar conductor 20^a. These cables, it will be understood, are to be constructed of sufficient strength to withstand the strains which may 105 be put upon them, and they are composed, in part or in whole, of insulating and waterproof material surrounding their conduc-

tors. The opposite end of the axial conductor 18 is electrically connected by a suitable rotary coupling 21 with a lead 22 extending from one pole of the battery 9. The other 5 pole of the battery is connected, as indicated at 23, with the shell of the buoy and thus grounded.

The lower attacher 3 has a suitable watertight casing 24 containing an electro-magnetic 10 net, of which 25 is the core and 26 the coil, the polar face 27 of the core being exposed at one side of the attacher. The lower end of the cable section 7 is secured to the casing 24 at 28, and its conductor 20^a is electrically 15 connected with one terminal of the coil 26. The other terminal of the coil is connected with a contact 29, which is located in a normally water-tight chamber 30, which is cut off from the magnet chamber by a wall 31.

20 Means are provided whereby contact with the submarine completes the circuit through the magnet coil, thereby energizing the magnet, and also releasing the downward extending cable section 8. Such 25 means may be widely varied. In the illustrated construction a plunger or trigger member 32 is mounted slidably in the front wall of the inclosure 30, the joint around it being rendered tight by a suitable stuffing- 30 box 33. In this construction the inner portion of the plunger constitutes one of the electrical contacts for closing the normally-open break in the magnet circuit, for which purpose it is so arranged as to have wiping 35 engagement with the curved extremity of the spring contact 29 when the plunger is pushed in. In this embodiment, also, the inner portion of the contact plunger forms part of a separable connection or coupling 40 between the attacher 3 and the downward extending cable section 8. Thus, an extension 34 of the plunger, which is made narrower than the electrical contact portion in order that it may be spaced from the contact 45 29, is formed with a slot 35, which receives a neck 36 on the inner end of a coupling member slide 37, which is mechanically connected with the upper end of the cable section 8. Upon the end of the neck 50 36 is a head 38, which normally holds the coupling slide 37 against movement outward through the bottom wall of the compartment 30. When, however, the plunger 32 is moved inward the head 38 is free to

55 pass through the slot 35 and the parts below, attached to the anchor, will thus be disconnected. The opening in which the slide 37 is mounted is normally rendered tight by a flexible boot 39, in general respects similar to the member 13, at the cable exit from the buoy. When the said slide is pulled out of the opening, water is free to enter the compartment 30, and, being a good conductor, will complete the circuit through the 60 coil of the magnet even should the gap not

be bridged by the engagement of the plunger 32 with the contact 29. In either event a circuit to ground, that is to say to the water, is completed through the coil. In no event, however, is water permitted to 70 enter the magnet chamber so as to short-circuit the energizing coil.

Secured at its ends to bracket lugs 40, at opposite sides of the polar face 27, are the ends of a circular fender 41, which encircles the remaining sides of the attacher so that the polar face is in effect located at one portion of the circular path. The said fender may be provided with spurs 42, of any suitable number and arrangement. 80 The contact projection 32, it will be noted, is located adjacent the said polar face and preferably centrally below it. Extending centrally above the said face is a bracket 43, which is stayed from the cable 6 by a chain 85 44 and terminates in a spur 45. The point of this spur projects slightly forward from the plane of the face 27 and is located at a sufficient distance laterally therefrom effectively to brace the magnet against being 90 pulled along a smooth surface, to which it may adhere.

The upper attacher 3^a, or as many attachers as may be located above the lowermost attacher 3, is preferably of the same 95 construction as that just described, except that the circuit arrangements are slightly different. Thus, in Fig. 7 the circuit which enters from the cable section 6 is branched. One branch passes through the coil of the 100 magnet, as described in connection with the attacher 3 to a contact 29^a, which is adapted to be engaged by a trigger 32^a. The other branch includes a conductor 46 in shunt with the magnet coil and leading to a 105 spring contact terminal 47 mounted upon the inner side of the wall 31^a. A plunger 48 of insulating material is mounted with a tight sliding fit in an opening in this wall and contains a conducting pin 49, one end of 110 which is normally in electrical connection with the contact 47 while its opposite end is in electrical connection with a conducting cap 70 on the end of the coupling member 37^a, which is electrically and mechanically 115 connected to the upper end of the cable section 7. The conductor 20^a and the terminal 70 are insulated from the body of the coupling member 37^a, as indicated at 71. The coupling member 37^a is normally held by 120 the trigger member 32^a in the manner described in connection with the attacher 3, and in this condition it holds the plunger 48 and its conducting pin 49 in the inward position, in which position the spring contact 47 is deflected sufficiently to insure electrical contacts at both ends of the pin. When the coupling member 37^a is released by inward movement of the trigger plunger 32^a, the plunger 48 is moved outward in the 125 130

wall 31^a by a spring 50, which thus breaks the contact between the pin 49 and the contact 47. A conical shoulder 51 may be provided upon the inner or upper end of the 5 plunger 48 to coöperate with a corresponding seat at the inner side of the opening in the wall 31^a, so that when the plunger is moved outward by the spring the tight joint against passage of water from the compartment 30 to the main compartment is insured.

Means are provided whereby the reserve of the cable section 6 within the buoy 2 is normally locked, so that the buoy is held 15 beneath the water, and whereby it is automatically released in order to permit the buoy to rise and float at a substantial distance from one or other of the attachers when the latter has been acted upon by a 20 submarine. Numerous embodiments of such means may be devised, but I prefer to provide a detent which coöperates with the reel 11 and which may be disengaged therefrom by the movement of a rudder when the buoy 25 is towed. As illustrative of such means I have shown a vertical rock-shaft 52 journaled in a suitably packed bearing in the lower part of the buoy and bearing at its 30 upper end a detent arm 53 which is normally engaged with a notch 54 in one of the flanges of the reel. To the lower end of the rock-shaft is secured a rudder 55. In the normal condition the rudder is held obliquely, as shown in Fig. 9, by the pressure 35 of the shoulder at one end of the notch 54 against the detent 53, movement in the direction of this pressure being prevented by a suitable stop, such as that indicated at 56. When the buoy is drawn through the 40 water the rudder 55 seeks to assume a central position, and in so doing moves the detent 53 away from the stop 56 and out of engagement with the projection 54. This 45 leaves the reel free to turn, and the buoy consequently shoots upward to the surface. The substantial amount of cable contained 50 upon the reel enables the marker to remain at the top throughout the corresponding range of depth of the submarine.

Means are also preferably provided for automatically illuminating the buoy. The preferred embodiment of such means is illustrated, but it will be understood that numerous other forms may be substituted. 55 In the said embodiment the buoy is provided with a central, vertical, tubular chamber 57, containing a slow-burning composition 58, capable of producing a flare at night and a smudge in the daytime. Such 60 marine lights are known for other purposes, and therefore this one does not require particular description. The composition is of a character to be ignited chemically by liquid contained in the glass balls 59 placed upon 65 the top of the composition and adapted to

be broken by the descent of a crusher 60. The said crusher is secured upon the upper end of a rod 61, which is slidable in a central guide 62 and bears a foot 63 at its lower end to bear upon the surface of the 70 cable supply upon the reel 11. A spring 64 contained in a chamber 65 presses this foot downward when it is permitted to do so by the unwinding of the cable from the reel, with the result that the crusher is 75 brought against the balls 59, thereby igniting the light. The upper end of the light chamber is covered by a dome 66 having an outlet orifice, which is normally tightly closed by a plug 67. This plug is driven 80 out by the gases generated in the light after the liquid contained in the balls 59 has acted upon the composition 58. It will be understood that the proportions should be such that the igniting device does not act 85 until the buoy has reached the surface.

The operation will now be briefly described. Let it be assumed that a submarine comes into contact with the lower attacher 3. The sliding of the side of the 90 vessel against any portion of the fender 41 will cause the device as a whole to roll upon the submarine until the polar face 27 and the contact 32 are brought against the vessel's side. This forces the plunger 32 inward, which releases the coupling member 37, thereby casting off the cable section 8, which extends downward to the anchor. At the same time the circuit through the magnet coil is completed by the engagement of 95 the plunger 32 with the contact 29, or by the entrance of water into the chamber 30, or by both, with the result that the magnet is energized and is held by attraction against the wall of the vessel. The movement of the boat now carries the attacher with it, the attacher being braced against slipping by the claw 45 in the manner already described, and the buoy 2 is drawn through the water, the anchor and parts below the attacher in question being left behind. As heretofore described the movement of the float turns the rudder or vane 55 so as to release the reel 11, with the result that the cable 6 may be paid out as 115 the float rises to and travels upon the surface of the water. The unwinding of the cable automatically ignites the marine light in the buoy in the manner described. The undersea boat is thus caused to tow a visual 120 signal, which keeps the surface of the water irrespective of the depth at which the boat may be proceeding.

If it is a lower attacher which is thus brought into action, the attacher or attachers above it are, of course, carried along. Any attachers below the one which may be engaged drop away. Thus, if the attacher 3^a is engaged by a submarine, it releases the cable section 7, with the result that the 130

attacher 3 is left connected to the anchor while the attacher 3^a and the buoy are carried away by the boat. Normally, as already described, an electrical path is completed through the attacher 3^a, around its coil 26^a, to the cable section 7, in order to lead current to the attacher or attachers below. When, however, the trigger 32^a of the said attacher 3^a is actuated, thus permitting the said attacher and the cable section 7 to separate, the branch around the magnet coil is broken at the circuit-breaking contacts 47, 51 at a region inaccessible to water, so that the magnet cannot be short-circuited. At the same time the gap in the branch through the magnet coil is completed in the manner described in connection with the attacher 3.

While the invention has been described particularly as a detecting apparatus it is to be understood that it is not necessarily so limited and that certain of its principles of construction, combination and operation may be embodied in anti-submarine devices of specifically different character.

25 What I claim as new is:

1. A submarine detector comprising the combination of a marker, a magnetic attacher including a magnet connected by a cable with the marker, means for anchoring the same, and means for automatically disconnecting the attacher from the anchorage.

2. A submarine detector comprising the combination of a marker, a magnetic attacher including a magnet, a cable connecting the marker and attacher, means for anchoring the marker and attacher below the surface, means for automatically disconnecting the attacher from the anchorage, and means for automatically paying out said cable.

3. A submarine detector comprising a buoy, a magnetic attacher including a magnet connected below the buoy, and means whereby the attacher is energized by contact.

45 4. A submarine detector comprising an anchored buoy, a magnetic attacher including a magnet connected between the buoy and the anchorage, and means whereby the attacher is energized and freed from the anchorage by contact.

5. A submarine detector comprising a buoy, an anchor, a sectional cable, a plurality of magnetic attachers each including a magnet connected between the sections of the cable, and means whereby contact at any one of said attachers energizes the same and frees it from the parts below.

6. A submarine detector comprising a buoy, a source of electrical energy therein, an anchor, an intermediate magnetic attacher including a magnet, cable means connecting the buoy, attacher and anchor, an electrical circuit including the source of energy on the buoy, an energizing coil in the attacher and a normally open gap at the at-

tacher, and means on the attacher actuated by contact for closing said gap and freeing the attacher from the anchor.

7. A submarine detector comprising a buoy, an anchor, an intermediate magnetic attacher including a magnet, cable sections connecting the attacher with the buoy and with the anchor, a separable connection between the attacher and the lower cable section, and means whereby contact energizes the attacher and releases said separable connection.

8. A submarine detector comprising a buoy, an anchor, an intermediate magnetic attacher including a magnet, cable sections between the attacher and the buoy on the one hand and the anchor on the other hand, a coupling connecting the lower cable section with the attacher, and contact means for opening said coupling.

9. A submarine detector comprising a buoy, an anchor, an intermediate magnetic attacher including a magnet, cable sections connecting the attacher with the buoy and with the anchor, a slide on the upper end of the lower cable section entering the wall of the attacher, means for preventing entrance of water around said slide, and trigger-controlled means on the attacher normally holding and adapted to release said slide.

10. A submarine detector comprising a buoy, a source of electrical energy therein, an anchor, an intermediate magnetic attacher including a magnet, cable means connecting the buoy, attacher and anchor, an electrical circuit including the source of energy on the buoy, an energizing coil in the attacher and normally open contacts at the attacher, a separable connection between the attacher and the section of cable extending downward therefrom, and a contact plunger on the attacher adapted to close said contacts on the one hand and to open said separable connection on the other.

11. A submarine detector comprising a buoy, means including a cable having a normally locked cable supply for anchoring the buoy below the surface, a magnetic attacher including a magnet connected with the buoy, and means for releasing the cable supply.

12. A submarine detector comprising a buoy, means, including a cable, a reel in the buoy and a lock for the reel, for anchoring the buoy below the surface, a magnetic attacher including a magnet connected with the buoy, and means for unlocking the reel.

13. A submarine detector comprising a buoy, means including a cable having a normally locked cable supply for anchoring the buoy below the surface, a magnetic attacher connected with the buoy, a rudder on the buoy, and means whereby said rudder will release the cable supply.

14. A submarine detector comprising a buoy, means including a cable, a reel in the

5 buoy and a detent for the reel, for anchoring the buoy below the surface, a magnetic attacher including a magnet connected with the buoy, and a rudder on the buoy connected with said detent.

15. A submarine detector comprising a buoy, a reel therein, a magnetic attacher including a magnet below the buoy, an electrical conductor cable on the reel extending 10 to the magnetic attacher, a source of electrical energy in the buoy, and an electrical connection entering axially of the reel between said source and the cable.

16. A submarine detector comprising a 15 buoy, illuminating means therein, a magnetic attacher including a magnet, a cable connecting the buoy and attacher and having a reserve in the buoy, and means whereby paying out of the cable from the buoy causes 20 said illuminating means to light.

17. A submarine detector comprising the 25 combination of a buoy, an anchor, an intermediate magnetic attacher including a magnet, cable connections between the buoy, attacher and anchor, means for automatically freeing the attacher from its anchor, a reel in the buoy wherein part of the upper cable section is wound, illuminating means carried by the buoy, and means including a 30 member bearing upon the supply of cable on the reel for controlling said illuminating means.

18. A submarine detector comprising the 35 combination of a buoy, a magnetic attacher including a magnet, an anchor, cable connections between the foregoing, combustible means in the buoy, means for automatically disconnecting the attacher from the anchorage, and means for automatically igniting 40 said combustible means.

19. A submarine detector comprising the 45 combination of a buoy containing a stoppered combustible chamber, a magnetic attacher including a magnet, an anchor, cable connections between the buoy, attacher and anchor, means for automatically disconnecting the attacher from the anchorage, means for automatically causing the paying out of the cable connection between the attacher 50 and buoy, and means controlled by the paying out of said cable for igniting the contents of said combustible chamber.

20. A submarine detector comprising the 55 combination of a buoy, a battery therein, a reel also in the buoy, a magnetic attacher including a magnet, an electrical cable extending from said reel downward to the magnetic attacher, means for preventing entrance of water to the buoy through the 60 cable exit, and means for releasably anchoring the buoy and attacher.

21. A submarine detector comprising a 65 buoy, a magnetic attacher including a magnet connected therewith, a circuit for energizing said attacher containing a normally

open inclosed gap, and means for automatically admitting water to close the gap.

22. A submarine detector comprising a buoy and an anchor, combined with a magnetic attacher including a magnet and cable 70 connections, said attacher having a fender adapted to roll upon the surface of a submarine in order to bring the active part of the attacher against the surface.

23. A submarine detector comprising a 75 buoy and an anchor, combined with a magnetic attacher and cable connections, said attacher having a magnetic face and a contact device adjacent thereto, and a circular rolling path extending in both directions therefrom.

24. A submarine detector comprising a buoy, an anchor, a magnetic attacher including a magnet, a cable connecting the attacher with the buoy, and a detachable connection between the attacher and the anchor, said attacher having a claw disposed at a 85 distance from its active face in the direction of the buoy to brace the attacher against the surface of a submarine. 90

25. A submarine detector comprising a buoy, a source of electrical energy therein, an anchor, an upper and a lower magnetic attacher between the buoy and anchor, said 95 attachers including energizing coils, cable sections connecting the buoy, attachers and anchor, separable couplings between the attachers and their downward extending cable connections, circuit connections between said source and the energizing coils of the 100 attachers including conductors passing through the cable sections, the coil of the upper attacher being branched from the circuit passing to the lower attacher, said branch containing a normally open gap and the circuit 105

of the coil of the lower attacher also having a normally open gap, contact operated means on each attacher for closing the gap of the corresponding coil and for casting off its downward extending cable connection, 110 means normally preventing entrance of water to the attachers at the separable connections, and means, including an inclosed circuit-breaker in the upper attacher, for automatically opening the downward-extending 115 circuit at a place inaccessible to water when the corresponding cable section is cast off.

26. In a submarine detector, the combination of a buoy, a magnetic attacher comprising a tight casing, an electro-magnet therein, having its polar face exposed, a source of electrical energy in the buoy, a cable section between the buoy and attacher, another cable section extending downward from the buoy, 120 a coupling between the attacher and the downward extending cable section, an electrical circuit extending from the buoy through the upper cable section to the attacher, a branch passing from said circuit 125 130

to the coil of the magnet and including a normally open gap, another branch passing to said coupling and thence downward in the lower cable section and including a normally closed circuit-breaker having its electrical contacts in a closed chamber in the attacher, means whereby said circuit-breaker is controlled by the coupling, and means operated by a trigger on the attacher for closing said normally open gap and disconnecting said coupling.

27. An anti-submarine device comprising the combination of an anchor, an electro-magnetic attacher including an electro-magnet, a buoyant member, cable connections between the anchor, attacher and buoyant member, means normally in open circuit for supplying the electro-magnetic attacher with current, and means whereby the attacher is energized on contact.

28. An anti-submarine device comprising the combination of an anchor, an electro-magnetic attacher including an electro-magnet, a buoyant member, cable connections between the anchor, attacher and buoyant member, means normally in open circuit for supplying the electro-magnetic attacher with

current, means whereby the attacher is energized on contact, and means for simultaneously casting off from the anchor.

30

29. An anti-submarine device comprising the combination of an anchor, an electro-magnetic attacher including an electro-magnet, a buoyant member, cable connections between the anchor, attacher and buoyant member, means normally in open circuit for supplying the electro-magnetic attacher with current, a contact device on the attacher controlling said circuit, and means whereby actuation of said contact device casts off the cable leading to the anchor.

35

30. In an anti-submarine device, a magnetic attacher including a magnet, an active face and a circular fender extending in both directions from said active face whereby the attacher will roll upon the side of a submarine until said face is brought into action.

40

In testimony whereof, I have signed my name to this specification, in the presence of two subscribing witnesses.
